United States Patent [19]

Hackamack

[11] Patent Number: Des. 275,659

[45] Date of Patent: ** Sep. 25, 1984

[54] ELECTRONIC TESTING DEVICE FOR A
MICROPROCESSOR

[75] Inventor: Paul Hackamack, Torrance, Calif.

[73] Assignee: Ugly Products, Gardena, Calif.

[**] Term: 14 Years

[21] Appl. No.: 339,667

[22] Filed: Jan. 15, 1982

[52] U.S. Cl. D10/75; D13/24

[57] CLAIM

The ornamental design for an electronic testing device for a microprocessor, as shown and described.

DESCRIPTION

FIG. 1 is a top and right front perspective view of an electronic testing device for a microprocessor showing my new design;

FIG. 2 is a right side elevational view thereof;

FIG. 3 is a rear elevational view thereof;

FIG. 4 is a left side elevational view thereof;

FIG. 5 is a bottom plan view thereof.

FIG. 1

FIG. 2

FIG. 3

FIG. 4

FIG. 5
